PERCY W. AULAR, OF TITUSVILLE, PENNSYLVANIA, ASSIGNOR TO THE TITUSVILLE IRON WORKS COMPANY, OF TITUSVILLE, PENNSYLVANIA, A CORPORATION OF PENNSYLVANIA.

VALVE FOR PUMPS.

Application filed December 28, 1926. Serial No. 157,489.

This invention relates to a valve mechanism which is more particularly intended for use in slush pumps.

Ordinarily such pumps have their valve seats forced into a passage in the pump body leading to the pump cylinder and a cover is placed over the opening in the body through which the seat is introduced, which cover normally serves as a buffer and a retainer for the spring whereby the valve is yieldingly held in engagement with the valve seat. It has been found in practice that the fluid under pressure has a tendency to wear the valve seat so that it will leak and also to destroy the adjacent parts of the passage leading to the pump cylinder due to the abrasive action of the grit, sand and the like in the fluid being pumped, thus making it necessary in a comparatively short time to replace the entire body of the pump which contains the cylinders.

It is the purpose of this invention to provide a pump in which such expensive replacement is rendered unnecessary and to that end this invention consists generally in mounting the valve mechanism in a cage or housing which is separate from the body of the pump but detachably connected therewith, which housing and the parts mounted thereon take practically the entire action of the material being pumped and can be readily replaced when worn out without necessitating replacement of the body containing the cylinder, thereby effecting a considerable economy in the industry which employs such pumps.

In the accompanying drawings:

Figure 1 is a fragmentary vertical section of one form of valve mechanism for slush pumps embodying my improvements. Figure 2 is a horizontal section taken on line 2—2, Fig. 1. Figure 3 is a fragmentary section similar to Fig. 1 showing a slight modification of my invention.

Similar characters of reference indicate like parts in the several figures of the drawings.

The numeral 9 represents the body of the

pump which may contain any desired number of pump cylinders, but in common practice two cylinders are employed and the body is provided with inlet and outlet passages through which the fluid to be pumped is conducted to and delivered from opposite ends of the cylinders. Inasmuch as the inlet and outlet passages are substantially alike it will be assumed that the passage of which the sections 10 and 11 from parts will serve either as an inlet passage or as an outlet passage, and the following description of the valve mechanism in this passage will apply to the several valves of the pump. A part of this passage is enlarged to form a pocket 12 which receives the valve mechanism. Within said pocket and around a part of the fluid passage in the pump body the latter is provided with an annular inner shoulder 13 and opposite this shoulder the body is provided with an opening 14 leading to the exterior of the pump body. Around the outer end of this opening 14 the pump body is provided with an annular outwardly facing shoulder 15.

Arranged within the pocket 12 is a valve cage or housing 16 preferably of circular form which has its inner end facing the inner shoulder 13 of the body and provided at its outer end with a head 17 which forms a cover for closing the opening 14, and within the cage the same is provided with a cavity or conduit 18 one end 7 of which is circular and opens lengthwise through the inner end of the cage while its other end 8 opens laterally through the side of the cage in register with the corresponding parts 10, 11 of the passage of the pump body. A leak-tight joint is produced between the inner end of the valve cage and the inner shoulder 13 of the body by a packing 19 consisting preferably of a rubber ring interposed between these surfaces, and a leakage through the joint between the head of the cage and the body of the pump is likewise prevented by a packing 20 having preferably the form of a rubber ring clamped between the outer shoulder 15 of the pump body and the in-

wardly facing shoulder on the outer end of the valve cage. This cage is removably secured in the pocket of the pump body by suitable fastenings consisting preferably of a plurality of bolts 21 passing through the external marginal parts of the cage or housing and into the adjacent parts of the pump body. Fitting in the longitudinal circular opening 7 of the cage is a valve sleeve or tubular bushing 22 which is provided at its inner end with an inwardly facing valve seat 23 and on its periphery with an outwardly facing annular shoulder 24 which engages the inner side of the pocket 18 around the longitudinal opening 7.

On the outer end of the valve bushing the periphery of the same is provided with an annular locking groove 25 which receives the bore portion of the inner packing ring 19. Owing to the elasticity of the latter the latter can be sufficiently sprung to pass over the outer end of the valve bushing and then spring into the groove 25. By this means the ring 19 performs the dual function of a packing to prevent leakage between the inner end of the cage and the pump body and also as a locking means for holding the valve bushing in its opening in the cage so that displacement of these members relatively to each other is prevented.

The valve in the present instance consists of a disk 26 of balata or some fibrous or elastic material which is arranged within the cavity of the housing or cage and movable toward and from the seat 23 of the valve bushing for closing or opening the passageway through the valve mechanism. On its top or rear side this valve disk is engaged by a top plate 27 and on its underside or front side this valve disk is engaged by a bottom plate 28 which is provided with depending arms 29 sliding against the bore of the valve bushing, said bottom plate and arms together forming a guide whereby the valve disk is maintained in proper position during its movement toward and from the valve seat on the bushing. The top and bottom plates 27, 28, are clamped against opposite sides of the valve disk by a fastening device consisting preferably of a bolt 30 engaging the central parts of the same.

For the purpose of causing the valve to close promptly a spring 31 preferably of helical form is employed, which spring engages its lower or inner end with the top plate of the valve disk while its upper or outer end engages with the bottom of a recess 32 in the head or cover of the cage, thereby serving to hold the valve yielding-
ly in its closed position. This valve is opened by pressure against the underside of the same and is closed by pressure applied to the upperside thereof in a well known manner.

When the valve disk, bushing, cage or as-

sociated parts become worn to such an extent that the same leak then the entire valve mechanism can be removed as a unit from the passage of the pump body by first detaching the bolts 21 and then lifting the cage or housing out of the pocket of the passage. Such lifting is facilitated by means of a ring 33 which is secured to the outer end of the cage and adapted to be connected with a hoisting device of any suitable character. After the cage is removed the lower or inner packing ring may be sprung out of the groove of the valve bushing and then the latter may be removed from the cage after taking out the upper valve plate, guide, bolt and spring. A new valve bushing, disk and other parts may now be substituted for those in the cage which were worn and then the cage may be restored in the pump body as a unit in its normal position.

As shown in Fig. 1, the face 34 of the valve disk is flat and engages with a corresponding flat valve seat 23, but if desired the marginal part of the face of the valve disk may be conical, as shown at 35 in Fig. 3, and co-operate with a seat 36 of corresponding shape at the upper end of the valve bushing, as shown in the same figure.

Each of these forms of my invention provides a combination of parts which can be easily removed when worn and replaced by new parts in the pump body as a unit, thereby avoiding the necessity of replacing the body of the pump containing the cylinders as has been necessary heretofore when the parts formed integrally with the body containing the cylinders become worn by the abrasive action of the mud laden fluid which was pumped in rotary drilling or similar operations.

I claim as my invention:

1. A valve mechanism for pumps comprising a body having a passage for the fluid, an opening extending from said passage to the exterior of the body and an internal shoulder around said passage, a cage movable through said opening and having a conduit registering with said passage, a valve bushing arranged in said conduit and provided at its inner end with a valve seat and with an inner shoulder engaging the inner side of said cage and provided at its outer end with an external groove, a packing arranged between said internal shoulder and the inner end of said cage and engaging with said groove, and a valve arranged in the cage and movable toward and from said seat.

2. A valve mechanism for pumps comprising a body having a passage for the fluid, an opening extending from said passage to the exterior of the body and an internal shoulder around said passage, a cage movable through said opening and having

a conduit registering with said passage, a valve bushing arranged in said conduit and provided at its inner end with a valve seat and with an inner shoulder engaging the inner side of said cage and provided at its outer end with an external groove, an elastic packing ring arranged between said inter-

nal shoulder and the inner end of said cage and engaging with said groove, and a valve arranged in the cage and movable toward and from said seat.

In testimony whereof I hereby affix my signature.

PERCY W. AULAR.
